UNITED STATES PATENT OFFICE.

FRANCISCUS C. J. DE BOTH, DECEASED, BY JACOBUS J. D. DE BOTH, ADMINISTRATOR,
OF NYMEGEN, NETHERLANDS.

METHOD OF APPLYING OR LAYING ASPHALT PLATES.

Application filed June 16, 1927. Serial No. 199,314.

The present invention, in its broad aspect, has reference to improvements and in methods of applying or laying bitumastic, asphaltic and asphaltic-granito plates on floors, 5 aisles, walls and the like to form a novel covering therefor. It has been found that asphalt plates of the type defined in my Patent #1,643,059, granted September 20th, 1927, when applied or laid, form a desirable, 10 wear resisting and durable surface covering which is free from dust, and which is both moisture and weather proof and of pleasing and artistic aspect or appearance. Heretofore, asphaltic or bitumastic bases have been suggested for floor and the like coverings, 15 but none as far as is known have met with practical success except the application of asphalt as a mass. Among the principal advantages of my method of laying asphalt plates may be briefly defined the following; 20 first, the plates may be laid with greater convenience and facility than asphalt in the mass thereby greatly reducing the cost in that a material saving is effected in time, labor and apparatus; it having been found 25 that two workmen can lay 100 square yards of surface in about 16 hours; second, the thickness of the surface coating may be varied by using plates of different thickness, 30 thereby adapting the coating to the requirements of estimated traffic thereon; third, in the specialized, quantity production of plates in a centralized plant a greater uniformity can be obtained, a saving in labor and equipment effected, and a better selection of raw 35 materials had at less cost than in the application of asphalt or composition to a surface in the mass; fourth, the plates can be sold at retail in any desired quantity to cover 40 any given area, and they can be applied by anyone by following simple instructions and without the use of special tools; fifth, an asphalt floor can be laid in a nursery, kitchen or other room in a dwelling where it 45 would otherwise be impractical or undesirable to lay such a floor on account of the excessive generation of heat, noxious fumes and vapors, and the like usually accompanying the application of asphalt in mass; sixth, 50 the plates can be readily taken up after having once been laid, and re-laid over another base, and replacements and repairs can be quickly, cheaply and effectively made, and; seventh, a surface covering of asphalt plates 55 formed in accordance with the present meth-

od and apparatus affords a high degree of insulation from heat, cold and sound, is impervious to moisture, air, gas and the like, can be quickly cleaned, and is possessed to the desirable inherent resiliency (or springiness) of bitumen or asphalt which cannot be had with the use of tile, concrete, and certain composition floorings. 60

With these and other objects in view the invention consists in the novel steps and 65 combinations of steps constituting the method, as will be more fully disclosed herein-after and particularly pointed out in the claims.

In the drawings wherein the application 70 of the method is illustrated diagrammatically:—

Figure 1, is a view of the laying of the initial plate,

Figure 2, is a view of the laying of the 75 second plate,

Figure 3, is a view of the laying of additional plates, and

Figure 4, view A is a detail of an elevated seam, and view B of a flattened or pressed 80 down seam.

The materials used in forming the asphaltic or bitumastic mass from which my plates are made are preferably compounded according to either of two formulas; the first 85 involving the use of ground asphalt rock and 15 or 20 per cent bitumen, and the second a mixture of asphaltastic (a commercial product) and a per cent of bitumen and sand to attain the desired consistency. The mass 90 is heated to a very high degree of temperature since the hardness of the plates produced from such materials bears a direct relationship to the temperature to which the mass is brought. 95

When it is desired to form asphaltic-granito plates, from 15 to 20 per cent very fine (about 00 degrees comminution) marble chips (without dust) is added to the asphaltic mass before it is cast, and the plates are subsequently scoured until the marble chips show through and the plates present a pleasing and smooth appearance. The method of forming the plates from the foregoing materials or stock is defined in my Patent #1,643,059 granted September 20th 1927, and in my co-pending applications covering 100 respectively the apparatus for forming the asphalt sheets, cutting the sheets, and scouring plates of the asphaltic-granito type, and 105 110

identified by Serial Numbers 268,696, 268-
697, and 268,698. For present purposes, it
may be stated that the materials or stock is
first formed into a sheet, then ironed and
5 rolled, after which the plates are cut to the
desired sizes and scoured or polished as the
case may be.

As has heretofore been stated, one of the
principal advantages attributed to the use
10 of plates in the laying of asphalt floors is the
ease with which such floors can be laid. The
present plates (A) may be laid either on
a wooden or concrete base (B) or floor,
but if wooden floor is used for a base pro-
15 vision for ventilation should be made be-
neath the floor to prevent dry rot. In applying
the plates, the first plate (C) is laid
preferably in the left hand corner (B) of
the room and spaced from the walls a dis-
20 tance of about the thickness of the plate.
The edges or peripheral margins are then
heated throughout their entire vertical ex-
tent with a blow torch to about the melting
temperature whereupon the plate is forced
25 to position. The next plate (E) is similarly
placed and treated and so on until the
surface is covered; the meeting edges of
the plates being smoothed down with a hot,
blunt trowel (F) as shown in Figure 4,
30 views A and B. In laying asphaltic-granito
plates the entire surface is polished after
laying the plates with a polishing machine of
any approved make. It will thus be seen
that the only essential implements required
35 to lay the present plate is a blow-torch and
a blunt trowel. An unskilled workman or
any other person can do the work quickly
and at very small cost, and repairs can be
easily made, it simply being necessary to
40 remove the worn or defective plate. So also
can the entire floor be taken up and relaid
with facility. In practice the plates are us-
ually made with a thickness of 10 mm. for
ordinary purposes and are 500 x 500 mm.
45 square, but these dimensions are subject to

wide variation to meet different traffic con-
ditions. They may also be laid in an as-
phalt emulsion where traffic conditions are
heavy, or where desired; and the plates may
also be dyed various attractive colors where
50 desired although dyed plates have been found
to be somewhat lacking in cohesiveness.

It is obvious that those skilled in the art
may vary the details of construction as well
as the arrangements of parts without de-
parting from the spirit of the invention,
and therefore it is not desired to be limited
to the foregoing disclosure except as may be
required by the claim.

What is claimed is:

The method of applying asphaltic or bit-
umastic plates to a foundation to be cov-
ered thereby, consisting in first placing a
plate in one corner of the foundation or the
like and slightly spaced from the wall about
65 the foundation a distance about the thick-
ness of the plate, then heating the marginal
portions of the plate throughout its entire
vertical extent to about the melting point of
the asphalt, and forcing the plate into engage-
70 ment with the wall so that the semi-liquid
asphalt adheres to the wall about the founda-
tion, then taking each successive plate and
first positioning it slightly spaced with re-
gard to the plate or plates last laid and heat-
75 ing its marginal portions throughout the ver-
tical extent thereof to about the melting point
of the asphalt and forcing it against the next
adjacent plates so that the heated, semi-liquid
asphalt at the edges of adjoining plates in-
80 termingles to form a homogeneous mass, and
then heating and pressing down all elevated
or bulged seams between the plates caused by
pressure on the heated edges or marginal por-
tions when the plates are forced to position.

85 In testimony whereof I affix my signature.

JACOBUS J. D. DE BOTH,
Administrator of the Estate of F. C. J.
de Both, Deceased.
